UNITED STATES PATENT OFFICE.

SAMUEL J. SHIMER, OF MILTON, PENNSYLVANIA.

CUTTER-HEAD.

SPECIFICATION forming part of Letters Patent No. 629,276, dated July 18, 1899.

Application filed January 10, 1899. Serial No. 701,769. (No model.)

To all whom it may concern:

Be it known that I, SAMUEL J. SHIMER, a citizen of the United States, residing at Milton, in the county of Northumberland and State of Pennsylvania, have invented new and useful Improvements in Cutter-Heads, of which the following is a specification.

My invention relates to rotary cutter-heads for woodworking machinery of that class or description known as "expanding" cutter-heads, which consist of two sections provided with flanges carrying the bits, one of which sections is movable, so that it may be caused to move away from or toward the other section to vary the width of the groove cut.

The object of the invention is to provide such cutter-heads with a scale by which the degree of expansion of the movable section can be readily determined, so as to cut a wider or narrower groove, as the case may be.

The invention consists in the novel construction and combination of parts hereinafter fully described and claimed.

In the accompanying drawings, Figure 1 is an elevation of a cutter-head provided with my improved scale. Figs. 2, 3, and 4 are similar views of the hub of the movable section, the adjusting-ring, and retaining-nut, showing them looking from different points. Fig. 5 is a central longitudinal section of the same. Fig. 6 is a plan view of the holding-nut.

In the said drawings the reference-numeral 1 designates the lower section of an expanding cutter-head, provided with flanges 2, formed with bit-seats 3 to receive the bits 4. This section is provided with a hub 5, having a screw-bolt 6 at the upper end provided with a jam-nut 7, and means for holding the retaining-nut hereinafter described and preventing it from turning. These parts, however, form no part of the present invention and a detailed description is therefore not necessary.

The numeral 8 designates the upper section of the head, which is movable with respect to the lower section and is provided with flanges 9, formed with bit-seats 10 in the lower sides to receive the bits 12. The said sections are provided with sleeves 13 and coiled springs 14 for expanding the same.

The hub of the inner or lower section is

formed with peripheral screw-threads 15, there being sixteen to the inch. Fitting on this hub is an adjusting-ring 16, having corresponding threads by which the adjustment of the two sections with respect to each other is effected. The adjacent ends of the hub of the upper section and the said ring are serrated, as usual in this class of heads. Above said ring and working on the hub of the said lower section is a retaining-nut 17.

The parts so far described may be of any ordinary or suitable construction.

The hub of the upper section is formed below the nut with a number of peripheral concentric circles, each of which is divided into four equal parts and designated by suitable characters, the upper circle being designated by a "0" and by the numerals "1," "2," and "3," consecutively arranged. The next circle is designated by the numerals "4," "5," "6," and "7," consecutively arranged, and the next circle by the numerals "8," "9," "10," and "11," also similarly arranged. Above the said ring the retaining-nut is formed with similar concentric circles, also provided with consecutively arranged numerals, but which run in a reverse direction. The adjusting-ring at the limit of its movement is formed with characters numbered "17^a," which will be in coincidence with the ciphers on the hub and retaining-nut when said ring is at the lower and upward limit of its movement. The upper end of said retaining-nut on its upper side is provided with four marks or characters "18" at equal distances apart. The said hub and retaining-nut below and above the adjusting-ring are provided with arrows pointing in opposite directions.

Before proceeding to describe the manner of using the invention I would say that in the present instance the head shown is designed to be used in connection with either grooving or tonguing bits. The grooving-bits when the head-sections are contracted to their limit partly overlap, but do not pass each other, and in expanding said sections the bits of one section move away from those of the other, whereby the groove is enlarged; but the expansion is such that the cutting edges are never far enough apart to be out of horizontal alignment, but follow each other to cut

the groove. The bits of the upper section cut the upper side of the groove and the bits of the lower section cut the lower side. When tonguing-bits are used, they overlap and 5 pass by each other, and the bits of the upper section cut the lower side of the tongue, while the bits of the lower section cut the upper side, being the reverse of that above described with respect to the grooving-bits, so that when 10 the sections are expanded the bits will be brought nearer to each other, thus cutting a narrower tongue. This arrangement of the bits, however, is not essential to the operation of the invention, as the grooving-bits 15 may be arranged to overlap each other, so that in expanding they will cut a narrower groove, while the tonguing-bits can be arranged to cut a wider tongue when the sections are expanded. Again, two heads may be employed, 20 one to cut the groove and the other the tongue.

The manner of using the invention is as follows: The hub of the stationary section having threads on its periphery sixteen to the inch and the adjusting-ring being correspondingly threaded it follows that at every quarter-revolution of the said ring the groove cut by the bits will be one sixty-fourth of an inch wider or narrower, according to the direction in which the ring is turned, and that a complete rotation of the ring will cause the groove cut to vary one-sixteenth of an inch. Supposing now that the adjustable section is at its lowest limit and the retaining-nut also at the lowest limit, then the characters on the 35 ring will register with the cipher-marks on the hub and nut, as seen in Fig. 1, and supposing, also, that the bits are seven thirty-secondss of an inch in thickness, so that the groove cut will be one-fourth of an inch wide, 40 if the adjusting-ring be now turned one-quarter of a revolution to the right the sections will be expanded one sixty-fourth of an inch, making the groove cut one-fourth of an inch wide plus one sixty-fourth of an inch. The 45 sections will be expanded one sixty-fourth of an inch each quarter-revolution of the adjusting-rings, so that a complete revolution will give an expansion of four sixty-fourths of an inch, and four revolutions will give an 50 expansion of one-quarter of an inch. The arrow on the retaining-nut indicates the direction the adjusting-ring is to be turned in expanding the cutters to cut a groove, while the arrow on the hub is to indicate the direction 55 of the movement for cutting a tongue, because the groove bits or cutters work inside a groove, while the tongue bits or cutters work outside the tongue, and hence the section moves in the opposite direction in expanding to cut an enlarged groove to that in 60 which it moves in cutting a tongue.

Should the expansion of the movable section be considerable, it may have given the groove cut an undesirable location within the 65 edge of the board. For readjustment of cutter-head on the spindle to locate the groove at the right place mechanically without the

use of a try-stand I make the thread of the top screw to agree with the thread proportions in the adjusting-ring and mark the head of the retaining-nut with four equidistant characters and provide the top screw on the upper side of its head with a double arrow to enable the operator to proportion his adjustments of the cutter-head up or down on 75 the spindle by moving the top screw to the right or left to agree with adjustment made upon head-sections. For example, the tongue and groove on opposite sides of the flooring-strips must be cut at same relative distance 80 from the bed of the machine, which carries the board as it passes through between the cutter-heads. Say one-fourth of an inch is allotted to the under part of the tongue and groove, one-fourth of an inch to the tongue 85 and groove proper, and seven-sixteenths to the edge of the board above the tongue and groove. These two relative positions for the cutter-head are had by resting the top screw upon the top of the spindle within the cutter-head. Should it be necessary, however, to change the thickness of tongue and groove to five-sixteenths for any portion of the flooring which is being made, loosen the set-screw so that the several sections of the cutter-heads 95 have a free movement and turn the adjusting-ring on the tonguing-head one full turn around. On the groove-head, turn the adjusting-ring one full turn around in the opposite direction. As specified on the several 100 heads, the tongue and groove cutters will now be set to cut five-sixteenths tongue and five-sixteenths groove, but by changing for the tongue we have raised the under tongue-forming bit one-sixteenth of an inch up, which 105 will cut a face five-sixteenths of an inch below the tongue, instead of one-fourth of an inch, to which the levels were first set. This makes it necessary to loosen the jam-nut about the top screw and turn the said top 110 screw one turn around and fasten the jam-nut. The cutter-heads will now be again adjusted to one level and will cut five-sixteenths tongue and groove.

From the above it will be seen that the workman or operator can readily determine at a glance the degree of adjustment to be given to the adjusting-ring to vary the distance between sections and can also readily tell the exact width of the groove cut by simply noting 115 the numeral with which the characters on the adjusting-ring coincide and adding to the width of the cutter the degree of expansion indicated by said numerals and characters.

It is not necessary that the hub-threads 120 described should run sixteen to the inch and the numerals and characters on the hub, retaining-nut, and adjusting-ring should be arranged exactly as illustrated; but I have found the arrangement shown as the most 125 convenient in use.

Having thus fully described my invention, what I claim is—

1. As an improved article, an expanding

cutter-head comprising the two sections one of which is provided with a hub having a predetermined number of screw-threads to the inch, the movable section provided with a hub having its periphery divided by a series of consecutively-arranged numerals into a number of equidistant parts, the correspondingly-threaded expanding-ring provided with a peripheral mark adapted to register with said numerals when said ring is rotated and the retaining-nut having an arrow or other character for indicating the direction in which the adjusting-ring is to be turned for widening and narrowing the groove, substantially as described.

2. As an improved article, an expanding cutter-head comprising the two sections one of which is provided with a hub having a predetermined number of screw-threads to the inch and having on its periphery an arrow or other character, the correspondingly-threaded adjusting-ring provided with a peripheral mark, and the retaining-nut having its periphery divided by a series of consecutively-arranged numerals into a number of equidistant parts adapted to register with mark on the adjusting-ring, substantially as described.

3. In an expanding cutter-head, the com-

bination with the section provided with a hub having a series of peripheral screw-threads of a predetermined number to the inch, of the movable section provided with a hub having its periphery divided by a series of consecutively-arranged numerals into a number of equal parts, the correspondingly-threaded adjusting-ring provided with peripheral marks, and the retaining-nut provided with a series of consecutively-arranged numerals similar to but running in the reverse direction to those of the hub of said movable section, substantially as and for the purpose specified.

4. In an expanding cutter-head, the combination with the retaining-nut having its upper end divided by a series of marks into a number of equidistant parts, of the top screw, the head of which is marked on the upper side by a double arrow, substantially as and for the purpose specified.

In testimony whereof I have hereunto set my hand in presence of two subscribing witnesses.

SAMUEL J. SHIMER.
